(57) **CLAIM**

The ornamental design for a stiffened member used for bumper reinforcement for automobile, as shown and described.

DESCRIPTION

FIG. 1 is a perspective view of a stiffened member used for bumper reinforcement for automobile showing our new design;

FIG. 2 is a front view thereof;

FIG. 3 is a rear view thereof;

FIG. 4 is a left side view thereof; the right side image is a mirror image of the left side view;

FIG. 5 is a top plan view thereof; the bottom plan view is a mirror image of the top plan view;

FIG. 6 is a cross-sectional view taken along lines 6-6 in FIG. 2 thereof; and,

FIG. 7 is an enlarged cross-sectional view taken along lines 7-7 in FIG. 2.

The broken lines in the drawings are for the purpose of illustrating unclaimed portions of the stiffened member used for bumper reinforcement for automobile and form no part of the claimed design. The dot-dash-dot lines represent the boundary of the claimed design and form no part of the claim.
